Milo B. Stevens & Co.

Attorney

UNITED STATES PATENT OFFICE.

WILLIAM H. FRIEDRICH, OF DYER, INDIANA.

ELECTRICAL CONDUIT.

Application filed December 20, 1923. Serial No. 681,897.

To all whom it may concern:

Be it known that I, WILLIAM H. FRIEDRICH, a citizen of the United States, residing at Dyer, in the county of Lake and State of Indiana, have invented new and useful Improvements in Electrical Conduits, of which the following is a specification.

This invention relates to conduits especially adapted for enclosing signal and other wires used along railway tracks.

Briefly stated, an important object of this invention is to provide a conduit of the character specified which is formed entirely from metal to resist the weather and fire.

A further and equally important object of the invention is to provide a conduit of the character specified wherein the hood of the same may be quickly detached without damage thereto to afford access to the wires should it be desired to correct irregularities in the system or install new wires.

Also, an aim of the invention is to provide novel means whereby the sections comprising the conduit are securely connected by the same fastening means which secures the conduit to the usual supporting posts.

A further object is to provide a conduit of the character specified which is of highly simplified construction, durable in use, and cheap to manufacture.

Other objects and advantages will be apparent during the course of the following description.

In the accompanying drawing forming a part of this application and in which like numerals are employed to designate like parts throughout the same,—

Figure 1 is a plan view of the improved conduit in use.

Figure 2 is a side elevation of the same.

Figure 3 is a detail longitudinal sectional view taken on line 3—3 of Figure 1.

Figure 4 is a vertical transverse sectional view taken on line 4—4 of Figure 3.

Figure 5 is a detail horizontal sectional view taken on line 5—5 of Figure 4.

In the drawing wherein for the purpose of illustration is illustrated a preferred embodiment of the invention, the numerals 5 designate a plurality of spaced posts upon which the improved conduit is mounted.

The body of the conduit consists of a plurality of lengths of channel shaped members 6 arranged in overlapping relation as illustrated in Figure 5 and those portions

of the lengths of channel shaped members which are overlapped are secured to the posts by fastening devices 7. More specifically, the fastening devices 7 which are preferably nails are extended through the base portions of the channel shaped sections and not only connect the sections but also secure the conduit to the spaced posts.

The side walls of the channel shaped sec-

tions have their upper edges provided with

depending side flanges 10 which terminate a

substantial distance below the base portions

of the several sections as illustrated in Fig-

ure 3. The depending side flanges 10 ef-

fectively strengthen the upstanding sides of

the channel shaped members and flatly con-

tact with opposite sides of the posts 5. Fig-

ure 5 illustrates that the upstanding side

walls of the channel shaped members and

the depending side flanges of the same co-

operate in the formation of sockets or

grooves at the ends of the several channel

shaped sections to receive the ends of the

adjacent sections whereby to establish a sub-

stantially water tight connection between

the several aligned sections.

The wires arranged within the conduit are

protected by a transversely curved metallic

hood 20, the side walls of which flatly con-

tact with the side walls of the depending

side flanges 10 and as illustrated in Figures

3 and 4 the lower edge portions of the side

flanges and the hood have aligned openings 21

for the reception of fastening wires 22 by

means of which the hood may be detachably

though securely held in place. The ends of

the fastening wires are bent down and then

up as illustrated in Figure 4 so that the same

are concealed from view and are more or less

protected.

In use, the metallic hood 20 forms a re-liable means for protecting the wires in the channel shaped conduit from the weather, dust, cinders and sparks. The improved con-

duit is especially valuable in protecting the

wires from damage by fire as the conduit is

strictly fire proof and sparks and cinders

from locomotives cannot burn the insulation

from the wires and possibly cause a short

circuit.

Also, as the conduit is entirely of metal the

same will not rot or deteriorate as the wood

conduits now in use do.

When it is desired to gain access to the

wires it is merely necessary to remove certain

of the fastening wires 22 and the hood or

any section of the same may be instantly detached. The desired addition or repair may be made and the hood quickly replaced, after which the wires 22 are again employed. Attention is directed to the fact that the wires 22 not only prevent the accidental removal of the hood, but also support the hood in its proper position on the conduit and prevent the hood from settling and possibly spreading.

10 ing.

Lateral branches 30 may be connected to the main conduit by means of couplings 31 and the branch or branches 30 may extend beneath the rails 33 and the cross ties 34.

15 I claim:—

1. A conduit of the character specified comprising a plurality of channel shaped sections having upstanding side walls provided with depending reinforcing flanges extending for the full length thereof and terminating below the lower edges of the side walls, the side flanges being spaced from the side walls and cooperating with the same to define sockets for the reception of the end portions of adjacent sections.

20 2. A conduit of the character specified comprising a plurality of channel shaped sections having upstanding side walls provided with depending reinforcing flanges ex-

25 tending for the full length thereof and terminating below the lower edges of the side

walls, the side flanges being spaced from the side walls and cooperating with the same to define sockets for the reception of the end portions of adjacent sections, and a transversely curved hood extending over said side flanges and having their lower edges arranged adjacent the lower edges of said side flanges.

3. A conduit of the character specified comprising a plurality of channel shaped sections having upstanding side walls provided with depending reinforcing flanges extending for the full length thereof and terminating a substantial distance below the lower edges of the side walls, the side flanges being spaced from the side walls and cooperating with the same to define sockets for the reception of the end portions of adjacent sections, a transversely curved hood extending over said side flanges and having its lower portions arranged adjacent the lower edge portions of said side flanges, the lower portions of said hood and the lower portions of said side flanges being provided with registering openings, and fastening devices extending entirely across the conduit and through said registering openings to hold the hood in place and limit spreading of the same.

40 4. In testimony whereof I affix my signature.

50 WILLIAM H. FRIEDRICH.
